UNITED STATES PATENT OFFICE.

ROBERT MORSE WITHYCOMBE, OF SYDNEY, NEW SOUTH WALES, AUSTRALIA.

FOUNTAIN BRUSH FOR AUTOMOBILES.

Application filed October 20, 1924. Serial No. 744,799.

This invention relates to fountain brushes and proposes the construction of an article of the class designated, which, while of general utility, is particularly adapted to the 5 cleansing of highly polished and easily marred surfaces, such as the outside surfaces of automobile bodies.

The invention has for one of its objects the provision of a fountain brush adapted to 10 deliver water to the surfaces to be cleansed in a jet having the form of substantially concentric laminæ, whereby concentric waves are produced upon said surface at the points of impingement of said laminæ, said waves 15 expanding outwardly, rippleslike, without mutual interference, carrying the dust and grit progressively away from the brush.

Another object of the invention is to provide a fountain brush in which the filamentous elements are arranged in spirally wound laminæ capable of spreading toward 20 their free ends and forming between them a convoluted space, flaring outwardly, so that water admitted to the base of the laminæ 25 and leaving at their free end loses velocity as it gains volume, issuing in a slow but voluminous jet, this being the condition best conducive to the removal of grit without scratching.

30 Other objects of the invention will appear as the description of the preferred embodiment thereof proceeds.

In the drawings:—

Figure 1 is a side elevation of my improved fountain brush for automobiles.

Figure 2 is a similar view, parts being broken away to show other parts in section.

Figure 3 is a section taken along the line 3—3 of Figure 2.

40 Figure 4 is a side elevation of a modified form of brush partly in section and in part broken away, and

Figure 5 is a fragmentary section taken along the line 5—5 of Figure 4.

45 Referring now in detail to the several figures, the numeral 1 represents, in general, the head of the brush which is held by any suitable means in the open end of a casing 2, leaving a space 3 in the rear end of said casing which functions as a reservoir. The back of the casing is preferably prolonged into a hollow boss 4 having a connector 5 of any desirable material held therein in any suitable manner as by striking in the material of said boss as shown at 6, causing it to

interengage with the connector 5. Said connector is preferably provided with spirally arranged corrugations 7 on its outer surface, having the form of a double taper over which a flexible hose 8 may be pushed, the seating of said hose being facilitated by rotating either the hose or the brush. The hose is adapted to be connected to any suitable source of water under pressure and which is indicated by the reference character 65 9. The connector 5 is formed with a bore 10 which places the reservoir 3 in communication with the source of water supply and the head of the brush is formed with any desirable number of suitable apertures 11 70 placing the reservoir in communication with the filamentous portion of the brush.

The head 1 of the brush is preferably formed of a solid portion 12, constituting one wall of the reservoir 3 and a filamentous portion 13 which extends outwardly from said solid portion and is preferably integral therewith. It is essential to the spirit of the invention that the filaments 14 which constitute the filamentous portion of the 80 brush be arranged in substantially concentric layers leaving substantially concentric spaces therebetween which communicate with the reservoir through the orifices 11. It is within the scope of the invention to 85 make the filamentous laminæ cylindrical but I have found it to be more practical, from a manufacturing standpoint, to construct the head of the brush from a continuous strip of material having a solid, 90 that is to say, uncut portion adjacent one edge and a filamentous portion adjacent the other edge, and to roll said strip into a convoluted body so that the filaments are arranged in spirally wound laminæ, the space between said laminæ being of similar form. In practice it is preferred to form the head 95 of the brush from a strip of rubber 16 cut along one edge into filaments, as described, and to superpose upon this strip a narrow strip 15 of solid, that is to say, uncut rubber overlying the uncut portion of the first strip but not extending over the filamentous portion thereof. A coating of suitable vulcanizing fluid or cement may be spread upon the contacting surfaces of one or both of said strips before winding them in convoluted form, the narrow strip forming a spacer for adjacent filamentous laminæ thereby giving width to the convoluted space between said 100 105 110 115

laminæ. The solid portion 12 may be vulcanized into a unitary mass by boiling the head of the brush for a suitable length of time in water.

5 It is not necessary, however, that the head of the brush be vulcanized for it may be secured in its convoluted form by any suitable means without transcending the scope of the invention.

10 The convoluted shape of the space between the laminæ has the advantage over concentric circular spaces of distributing the water uniformly throughout said space, even though the water emanates from the reservoir in a single one, or a small number of orifices.

The filaments 14 are preferably cut slightly wider at the base than the thickness of the strip from which they are formed so 20 that they constitute, adjacent the base, a relatively stiff wall, the filaments lying so close as to substantially prevent lateral leakage from one convolution of the spiral space to another. By reason of their length the 25 filaments become more flexible toward their free ends so that they separate slightly, not only under pressure of the brush against a surface but by virtue of the water within the convoluted space, causing the space to 30 become progressively more capacious as it approaches the free end of the brush. This has the effect of reducing the velocity of the water in passing through said convoluted space, at the same time increasing the volume 35 thereof so that the water issues from the end of the filamentous portion in a relatively slow and voluminous jet. This ensures the safest and most efficient cleansing action, for it is well known that, when water 40 impinges with great force upon the grit encrusted upon the surface of the automobile body, scratching or marring of the surface is apt to result.

The convoluted nature of the space between the filamentous laminæ determines the 45 form of the issuing jet of water, which impinges upon the surface to be cleansed in a succession of non-interfering, substantially concentric waves which expand from under the brush in a succession of ripples carrying 50 the dirt outwardly from the filaments of the brush and preventing its being ground into the finish of the automobile by the rubbing action of the brush.

55 Furthermore, the flat shape of the filaments at the base ensures the formation of well defined channels so that the water entering from the reservoir will spread circumferentially in a uniformly distributed film, keeping the filaments of adjacent layers apart. This, together with the flaring characteristic of the filaments under the pressure 60 of the water, causes the brush to be absolutely self-flushing so that no grit will be retained therein through capillary action or 65

any other cause. The action of the brush is entirely different in principle from that of an ordinary bristle brush. In a bristle brush, where the filaments are not arranged spirally, and are not comparatively close and flat adjacent the base, there are no well defined paths into which the water can issue and uniformly distribute itself. Moreover, the bristles group themselves into clusters which stick together by capillary attraction, 70 the water flowing around the outside of the cluster of bristles in undistributed streams, most of it running off of the lower side of the brush without impinging at all upon the automobile so that a more intimate rubbing 80 of the brush against the surface is required to effect the desired cleansing. The capillary attraction between the bristles of a cluster also causes the grit over which the brush moves to be drawn into the cluster between 85 said bristles, which grit is not only rubbed into the surface of the automobile during the operation of the brush, but is retained in the brush when the water is turned off so that the brush is not self-cleansing, and 90 therefore unsafe to use in contact with a highly polished surface.

In the modified form of my invention shown in Figures 4 and 5 the filamentous strip of rubber 16 and a narrow strip of corrugated material 17, preferably metal, are wound together. In this way series of openings 18 are formed at the inner end of the filamentous strip which afford communication between the reservoir and filamentous portion of the brush thereby obviating the need of making orifices 11 in the brush head after the latter has been rolled.

While I have here shown and described what I believe to be a practical form of my invention, yet it is to be understood that numerous changes and alterations in the several parts or the substitution of equivalents for elements herein shown and described may be made without departing from the spirit of the invention.

Having described my invention what I claim as new and desire to secure by Letters Patent, is:—

1. A fountain brush, comprising a cup-shaped casing having a hose connection, and a head closing said casing and having a filamentous portion arranged in the form of convoluted laminæ and defining between said laminæ a convoluted passage in communication with the casing.

2. A fountain brush, comprising a cup-shaped casing having a reservoir and a hose connection, and a strip of rubber having a filamentous portion at one edge, said strip being rolled to form a solid head with filaments, said filaments being arranged in convoluted laminæ to define between them a convoluted passage, the solid portion of the head sealing the casing and having passages

therethrough communicating with said chamber and said convoluted passage.

3. A fountain brush, comprising a cup-shaped casing having a reservoir and a hose 5 connection communicating therewith, a strip of rubber having a filamentous portion at one edge, and a strip of corrugated metal, both of said strips being rolled together to form a head having a base, the filaments being arranged to form convoluted laminæ defining between them a convoluted passage, the metal strip in said head affording channels communicating with said passage and the reservoir.
- 10 4. A fountain brush, comprising a cup-shaped casing having a hose connection and a head comprising a convoluted flexible strip having slits in one of its edges and having its opposite edge secured in the open 20 end of said casing, and means to permit the

passage of water from said casing to the space between the convoluted slitted edge of said strip.

5. A fountain brush, comprising a substantially cup-shaped casing having a hose 25 connection, and a head seated in the open end of said casing, said head comprising a strip of material having projections on one of its faces and a second strip of flexible material having slits along one of its edges, 30 said strips being wound together with said first-named strip between the convolutions of the unslotted portion of said second-named strip and the slotted convoluted edge of said second-named strip extending beyond 35 the open end of said casing.

In testimony whereof I have hereunto set my hand.

ROBERT MORSE WITHYCOMBE.
